UNITED STATES PATENT OFFICE.

ROBERT TURNER, JR., OF DETROIT, MICHIGAN, ASSIGNOR TO D. M. FERRY
& CO., OF DETROIT, MICHIGAN, A CORPORATION OF MICHIGAN.

DISPLAY-CASE.

No. 836,416.

Specification of Letters Patent.

Patented Nov. 20, 1906.

Application filed August 21, 1905. Serial No. 275,018.

To all whom it may concern:

Be it known that I, ROBERT TURNER, Jr., a citizen of the United States, residing at Detroit, county of Wayne, State of Michigan, have invented certain new and useful Improvements in Display-Cases, of which the following is a specification, reference being had to the accompanying drawings, which form a part of this specification.

10 My invention is designed to provide an improved display-case, the same being adapted for various uses, and has special adaptation as a display-case for packages of seeds and analogous articles, the same being more specially devised as a display-case for retailers of the goods.

15 The aim of my invention is to provide a case of this nature provided with a series of trays for holding the goods, the trays being removable, so that they may be stored away 20 in the case in a compact form for shipment and storage, the construction of the device being such that the trays may readily be arranged in position for efficient display in a 25 convenient and simple manner.

25 To these ends my invention consists of the construction, combination, and arrangement of devices as hereinafter described and claimed, and illustrated in the accompanying drawings, in which—

30 Figure 1 is a view in perspective illustrating my invention with the case open and arranged in position for use. Fig. 2 is a view in section on the line 2 2, Fig. 1. Fig. 3 illustrates a modification in perspective. Fig. 4 is a view in plan with the cover and the trays removed. Fig. 5 is a similar view and embodying the modification shown in Fig. 3. Fig. 6 is a detail view showing one end of the 35 case and one of the trays in vertical section longitudinally of the case. Fig. 7 is a view in perspective embodying certain features of construction with case in open position for use. Fig. 8 is a vertical section on the line 40 8 8, Fig. 7.

45 I carry out my invention as follows:

In the drawings, *a* represents the body of my improved case provided with a lid or cover *b*, said cover preferably having a 50 hinged engagement with the body, so that it may be thrown up into elevated position.

A series of trays is indicated at *c*, *d*, *e*, and *f*. To support such trays the case is provided with end brackets, indicated at *g*, said

55 brackets arranged to be folded within the case in knockdown position. As indicated more particularly in Figs. 2 and 4, the brackets *g* may be hinged to the bottom of the case, as indicated at *h*, so as to be folded down upon the bottom of the case, as indicated in Fig. 4.

A modified form in the construction of the brackets is shown in Figs. 3 and 5, in which the brackets are connected by a back strip, (indicated at *i*), the end brackets *g' g'* having a 60 folding engagement with the back strip, as by a flexible connection with said strip. For smaller cases the brackets and the back strip may be formed, for example, of pasteboard, the end brackets folding rearwardly against 65 the back strip, said brackets and back strip being constructed independently of the case, so that they may be removed and folded and laid down upon the bottom of the case. The end brackets are constructed with a series of 70 steps, as indicated in the drawings, so that the different trays may be supported thereupon at different elevations. To save room, I prefer to make the brackets of thin material. In larger cases I prefer to make them 75 of sheet metal hinged at their lower edges to the bottom of the case, as shown in Figs. 2 and 4. The trays are each provided at their extremities with supporting metal clips, (indicated at *j*), preferably made of sheet metal 80 engaged with the corresponding trays in a suitable manner, the clips projecting outward, so as to fit over and upon the upper edge of the corresponding end brackets, as illustrated more particularly in Figs. 1 and 6. As 85 so constructed it will be readily observed the trays may each be lifted off from the end brackets, the trays when removed from the brackets being located within the body of the case for storage or shipment, the size of the 90 body of the case and the trays being so arranged that the trays may fit properly within the body of the case and allow the cover to be closed down thereover. The cover and end brackets are preferably provided with 95 100 suitable hooks and eyes, as indicated at *k*, to support the cover in elevated position.

What I claim as my invention is—

1. A display-case having in combination an inclosing body, folding end brackets each 105 formed with a series of steps, a strip connecting said brackets, and a series of trays supported upon said brackets, said brackets and

the connecting-strip being removable from the body.

2. A display-case having in combination an inclosing body, folding end brackets, each formed with a series of steps, additional means to connect said brackets and a series of trays, each at its extremities provided with clips whereby the tray may be supported upon the upper edges of the brackets, and whereby the trays may individually be lifted vertically off from the end brackets.

3. A display-case having in combination an inclosing body, folding end brackets, each formed with a series of steps, a back strip connecting the rear edges of said brackets,

and a series of trays each provided at its extremities with clips whereby the tray may be supported upon the corresponding upper edges of the brackets, and whereby the trays may be individually lifted vertically off from the end brackets, said brackets and the back connecting-strip being removable from the body.

In testimony whereof I have signed this specification in the presence of two subscribing witnesses.

ROBERT TURNER, JR.
